BURNER FOR THE FIRING OF FURNACES

William Armstrong Woodeson, Gateshead-on-Tyne, England

Application December 13, 1932, Serial No. 647,017
In Great Britain August 22, 1932

10 Claims. (Cl. 110—104)

Although the performance of burners such as those of my pending application Serial No. 449,526 filed May 3, 1930 and Letters Patent No. 1,885,067 is very satisfactory, the equipment is 5 recognized to be capable of improvement and the present invention is the outcome of considerable experimentation directed largely to the feature of air distribution, one of the results being to produce a burner specially adapted for firing 10 in a horizontal position with the minimum of refractory material in the furnace tube. An important feature consists in injecting parts of the required secondary supply of air as jets well into the centre of the stream of fuel and primary air 15 discharged into the burner through a Venturi tube or its equivalent, liberation of such injected air occurring in a direction substantially perpendicular to the direction of flow and only after it has been mechanically constrained and 20 conducted across the stream for a considerable distance. The injecting means in effect constitute baffles encountered by the stream soon after leaving the Venturi tube or feed supply pipe and before it reaches the usual deflector and the turbulence due to such baffles is augmented by the 25 issuing secondary air jets. The secondary air is admitted to the burner from a common chamber through two independently controllable series of openings and the air inlet to this chamber 30 is in turn controlled by a member which although angularly adjustable is so shaped as to continue to give to air a bias towards the said openings which control the quantity of air entering the various parts of the burner.

35 In the accompanying drawings Fig. 1 is a front elevation and Fig. 2 a longitudinal section of the improved equipment for use with pulverized fuel. Fig. 3 is a view similar to Fig. 2 of parts modified to enable the equipment to be used with 40 liquid fuel.

Referring first to Figs. 1 and 2, a furnace front is employed comprising a casing 1 adapted to be bolted to the furnace, with the aid say of bifurcated lugs 2 spaced apart by 90° around the flange 45 3, and having an upper wall 4 which is curved to form an elbow-like continuation of a vertical secondary air inlet duct 5. A plate 6 bolted to the said casing has an ash door opening 7, an opening 8 to receive the burner setting 9 and 50 an opening 10 leading to the duct continuation aforesaid, such last referred to opening being controlled by a flap valve 11 which when closed is vertical but can be turned hingewise about a horizontal axis 12 arranged transversely of the 55 burner to admit more or less air to a casing 13

removably secured to the plate 6, said casing enveloping part of the burner and setting and being completed by a cover 14 which carries the primary air and fuel connection or Venturi tube 15 as well as an inspection eye 16, and controlling gear for the secondary air supply. The interior of the casing 1 is so ledged as to enable refractory material 17 to be built in between the burner setting 9 and the casing in order to protect both from being damaged by flame. Proceeding from the cover 14 the burner comprises a cylindrical body 18 extending to say half the depth of the casing 13 which receives the secondary air, followed by two concentric cylindrical walls 19, 20 of different axial length, the shorter wall 19 of larger diameter being fixed to the burner setting 9 and the longer wall 20 of smaller diameter extending with clearance into the burner setting, so as to form an annular space 21. An annular set of ports 22 is provided in the 75 burner to admit air around the primary air and fuel connection or Venturi tube 15 and a similar set of ports 23 is provided to admit air to the annular space 21 referred to from which it may escape in part through an annular gap 24. Extending inwards from the said annular space 21 are a number of nozzles 25 or air injection tubes, said tubes being arranged in any convenient way such as in one or more annular series, each tube being radial. Or the tubes, which 85 may be of equal or unequal lengths might be helically arranged. In any case they are distributed between the Venturi tube 15 and a longitudinally adjustable deflector 26 complete with flare 27 fitted in the mouth of the burner. 90

The two annular sets of ports 22, 23 in the burner are independently adjustable by separate ported sleeves 22^a, 23^a which may be rotated from the outside thus enabling the secondary air entering the burner to be controlled to a very fine 95 degree, it being possible to force the greater quantity through the air injection tubes 25 into the centre of the fuel stream if desired while a minimum of air is allowed to enter the burner through the remaining ports. 100

In the illustration, the rotation of the sleeve 23^a is shown as effected by a spur wheel 28 upon a spindle 29 journalled in the cover 14 and operated by a hand wheel 30 the wheel 28 meshing with teeth 23^b upon the sleeve. A hand wheel 31 105 is similarly geared to the sleeve 22^a which is toothed at 22^c. The effect of the injection tubes 25 is enhanced by forming the flap valve 11 with a concave curved surface 11^a facing the elbow extension 4 into which it extends when closed, 110

the free edge 11^b terminating at a wall 11^c concentric with the pivotal axis 12 of the valve, there being little or no increase in air delivery until the free edge 11^b leaves the elbow extension 4, 5 at which time the curved surface 11^a acts, and will thereafter continue to act, with further opening movement, to direct air smoothly towards the ports 22, 23 thereby guiding it, without forming eddies, to the various parts of the burner. The 10 pivoted flap valve 11 can be adjusted, and may be operated in any convenient way by any suitable means such as a lever handle 32 co-operating with a slotted guide 33 to which it can be clamped at any desired position by a nut 34.

15 Regulating and admitting the secondary air into the burner in the way described ensures a good mixing of air and fuel which results in rapid and complete combustion.

The adjustable deflector 26 and flare 27 gives 20 the operator complete control over the velocity of air and fuel being discharged from the burner into the furnace, and enables the point at which the coal commences to ignite to be fixed immediately in front of the burner mouth and thus 25 protect it from damage by the flame.

This control is very useful in case of ship installations where the bunker coal may vary greatly in percentage of volatile content.

With certain coal which has a very high volatile content the fuel ignites very readily and the 30 flame may commence inside the burner, and cause damage to it.

This can be overcome by drawing the deflector and flare up further into the burner which can be done by a pull applied to a draw rod 35 passing through the cover 14 thereby increasing the velocity at the burner mouth and carrying the point at which combustion commences just in front of the burner mouth where no damage to 40 the burner can take place.

45 Fig. 2, is a conical air director associated with the ports 22, an aperture 37 therein being provided to avoid obstructing the view through the inspection eye 16.

The burner described, suitable for pulverized fuel can also be adapted to oil fuel firing, as indicated in Fig. 3 where the oil fuel burner 38 is placed through the centre of the burner with the sprayer tip 39 inside the flare 27 of the deflector 50 26 the flame being controlled by adjusting the positions of the deflector 26 and oil fuel burner in an axial direction up or down the burner. Except in these respects the form of device shown in this figure is the same as that shown in the other views.

55 What I claim is:—

1. In a furnace firing equipment, a tubular conduit, a Venturi tube for discharging a mixture of air and fuel into said conduit, an air chamber surrounding said conduit, a plurality of radially arranged air nozzles extending well into said conduit at a point beyond the discharge of the air and fuel stream into the conduit and forming a communication between the air chamber and the interior of the conduit, a housing surrounding both the conduit and the air chamber and provided with a plurality of ports some of which have direct communication with the conduit and others of which have communication with the 60 conduit through the air chamber and the aforementioned nozzles, an air inlet to said housing, and a valve for controlling the inlet of air to the housing, the parts operating as and for the purpose described.

70 2. A furnace firing equipment of a construction

such as defined in claim 1, wherein independent controls having independent operating means are provided for controlling the passage of air through the ports which have communication directly with the conduit and through the ports which have communication with the conduit through the air chamber and air nozzles.

80 3. A furnace firing equipment such as defined in claim 1, wherein the valve for controlling the admission of air to the housing is provided with a concave surface facing the housing air inlet for directing air smoothly towards the air inlet openings to the burner conduit and the air chamber.

85 4. A furnace firing equipment of a construction such as defined in claim 1, wherein the valve for controlling the inlet of air to the housing is pivotally mounted and is provided with a concave surface facing the housing air inlet and is further provided with a curved wall portion arranged in separated relation to the wall of the housing air inlet when the valve is closed, said curved wall portion being coaxial with the pivotal axis of the valve and acting in conjunction with the wall of the housing air inlet to prevent any appreciable increase in air delivery to the housing as the valve is opened until the valve is approximately completely opened.

90 5. In a furnace firing equipment, a burner comprising a tubular conduit, a Venturi tube for discharging a mixture of primary air and fuel into said conduit, an air chamber surrounding said conduit, a plurality of air nozzles extending into said conduit at a point beyond the point of discharge of the Venturi tube and forming a communication between the air chamber and the interior of the conduit, secondary air inlets for said conduit communicating directly with the conduit, secondary air inlets for said conduit communicating with the conduit through the 100 afore-mentioned air chamber and nozzles, means to control the admission of secondary air through said secondary air inlets which communicate with the air nozzles, an adjustable deflector in the discharge end of the conduit, and manually operable means for adjustably positioning said deflector for controlling the point of ignition of the fuel and the length of the burner flame.

105 6. A furnace firing equipment for use with a furnace having a horizontally disposed tubular burner setting, a burner comprising a tubular conduit disposed within said setting and cooperating with said setting to form an air chamber surrounding said conduit, the inner end of said burner conduit having communication with the 110 furnace through the inner end of the burner setting, the outer end of said conduit carrying a Venturi tube adapted to discharge a mixture of primary air and fuel into said burner conduit, secondary air inlets communicating with the 115 conduit and with the air chamber surrounding the conduit, and air jets extending radially into the conduit at a point intermediate its ends and at a point beyond the discharge end of the Venturi tube and forming a communication between the 120 interior of the conduit and the aforesaid air chamber, the parts operating as and for the purpose described.

125 7. A structure such as defined in claim 6, wherein there is an adjustable deflector within the discharge end of the burner conduit and manually operable means are provided for adjusting and moving said deflector longitudinally of the conduit.

130 8. In a furnace firing equipment a tubular con-

duit, a Venturi tube for discharging a mixture of primary air and fuel into said conduit said Venturi tube being of a diameter considerably less than the diameter of the conduit and positioned with its axis coinciding with the longitudinal axis of the conduit, an air chamber surrounding the conduit, a plurality of air nozzles extending into the conduit between the discharge end of the Venturi tube and the discharge end 5 of the conduit and forming a communication between the air chamber and the interior of the conduit, and means for controllably admitting secondary air to the air chamber, the parts operating as and for the purpose described.

10 9. A structure such as defined in claim 8, wherein additional means is provided for controllably admitting secondary air directly into the conduit independent of any passage of the air through the air chamber or nozzles and at points 20 in the conduit in front of the nozzles.

15 10. In combination with a furnace having an opening in its front wall carrying a horizontally disposed tubular burner setting with open ends, a burner, said burner comprising a tubular con- 25

duit concentrically arranged within the tubular burner setting and having an open end adjacent the open inner end of the setting, an air chamber between the burner conduit and the tubular burner setting, nozzles extending into the burner conduit and forming a communication between the interior of said conduit and the air chamber, a housing surrounding that portion of the burner setting and the burner conduit which extends outwardly beyond the furnace face, a secondary air inlet for said housing, a valve for controlling the passage of air from said inlet to said housing, a valve controlled opening forming a communication between the burner conduit and the housing, a valve controlled opening forming a communication between the air chamber and the housing, the outer end of said burner conduit carrying a Venturi tube the inner end of which extends well into the burner conduit and is arranged with its axis coinciding with the longitudinal axis of the burner conduit, the parts operating for the purpose described.
